Patented May 13, 1924.

UNITED STATES PATENT OFFICE.

GEORGE H. GREIMAN, OF GARNER, IOWA.

CLEANING SCRAPER FOR EXCAVATORS.

Application filed March 16, 1923. Serial No. 625,575.

To all whom it may concern:

Be it known that I, GEORGE H. GREIMAN, a citizen of the United States, residing at Garner, in the county of Hancock and State 5 of Iowa, have invented certain new and useful Improvements in Cleaning Scrapers for Excavators; and I do hereby declare the following to be a full, clear, and exact description of the invention, such as will enable 10 others skilled in the art to which it app pertains to make and use the same.

My invention provides an improved cleaning device or scraper for excavators of the power-driven type, wherein excavating de 15 vices, variously indicated as shovels, buckets, spades, or scoops, are employed, and is in the nature of an improvement on or modification of the scraper disclosed and broadly 20 claimed in my U. S. Letters Patent #1, 449,224, issued March 20, 1923 and entitled "Cleaning scraper for excavators."

A commercial form of the invention is illustrated in the accompanying drawings, wherein like characters indicate like parts 25 throughout the several views.

Referring to the drawings:

Fig. 1 is a plan view, with some parts sectioned and some parts broken away, showing portions of the framework and of the 30 elevator of an excavator and showing a pair of my improved scrapers operatively applied to the elevator; and

Fig. 2 is a vertical section on the line 2—2 of Fig. 1.

The numeral 3 indicates the frame structure of an excavator, to the rear portion of which is secured axially aligned laterally spaced shaft bearings 4 in which a power-driven shaft 5 is journaled.

A vertically oscillatory excavator boom is shown made up of laterally spaced beams 6 rigidly tied together by cross bars 7. The beams 6, at their upper ends, are provided with bearings 8 that are pivoted on the 45 shaft 5 or otherwise arranged to move concentrically around the axis of said shaft.

Between the beams, the shaft 5 is provided with a heavy sprocket wheel 9. The excavator belt 10, in the form of a heavy 50 link or sprocket chain, is arranged to run over the sprocket 9 and over a similar sprocket, not shown but which, in practice, is suitably mounted at the free end of the boom.

Certain of the links of the belt or chain 10 are provided with flat outstanding arms

11, which, at their outer ends, carry curved excavator scoops or spades 12 of a character that will pick up the load at their front edges and discharge the same at their rear 60 lower edges, the discharge taking place as the scoops or spades make the upward turning movement around the shaft 5 and sprocket 9.

The scoops or spades 12 project laterally 65 on opposite sides of their arms 11 and, hence, for commingling the inner surfaces of these scoops or spades, I provide a pair of laterally spaced cleaning scrapers located one on each side of the sprocket 9. In the 70 arrangement illustrated, each scraper comprises an arm intermediately pivoted on or around the shaft 5 and provided at each end with a scraper blade. In the commercial form of the scraper, each arm is 75 made up of two channel bars 13, the inner ends of which are overlapped and rigidly connected at 14 by rivets or bolts and between said rivets or bolts are split to form an elongated loop 13^a. The loop 13^a 80 embraces the shaft 5 and, by trunnions 15, are pivoted to bearing sleeves 16, which, in turn, are journaled on the shaft 5. By this arrangement, the arm 13, by virtue of its trunnions 15, is pivoted for lateral oscillatory 85 movements and by its sleeve 16 is arranged to rotate on the shaft 5. As shown, the bearing sleeve 16 is split or divided, the sections thereof being rigidly connected by small nut-equipped bolts 17. To the opposite ends of the arm 13 are secured scraper blades 18, the rectangular corners of which are arranged to work close to the inner surfaces of the scoops or spades 12 and close to the carrying arms 11, as best shown at 90

the left in Fig. 1. The arrangements of the two scrapers on the opposite sides of the sprocket 9 are the same and as above described, but they are in reverse relation so that the scraper blades 18, when turned 95 away from their operative positions, as shown at the right in Fig. 1, will be positioned with their outer edges reversely oblique to the axis of the shaft 5. To act upon these oblique edges in the position 100 just stated, I provide stop devices in the form of beveled rollers 19 journaled on a non-rotary spindle 20, the outer ends of which are mounted for sliding movements in elongated seats formed between the under 110 edges of the beams 6 and the upper edges of U-shaped guide straps or brackets 21 that

are rigidly secured at their ends to said beams. The spindle 20 is positively held against rotation, but permitted sliding movements in a general direction toward 5 and from the shaft 5, by anchoring pins 22, the ends of which are secured to crossbars 23 rigidly attached to the under edges of the beams 6. Coiled springs 24, placed around the pins 22 and compressed between the 10 brackets 23 and the ends of the spindle 20, yieldingly press the latter toward the shaft 9 and hold the stop rollers 19 positioned to intercept the blades 18 and thereby stop and yieldingly hold the scrapers in their operative 15 positions shown in the drawings. As shown, the movement of the spindle 20 toward the shaft 9 is limited by small stop pins 25 and 26 applied in the outer ends of the pins 22.

20 Rigidly secured to the non-rotary spindle 20, just inward of the stop rollers 19, are segmental cams 27, the function of which will presently appear.

By reference to Fig. 1, it will be noted 25 that the adjacent inner edges of the scraper blades 18, when in operative position as shown at the left in Fig. 1, are spaced apart much less than the width of the chain or belt 10 and that, hence, to permit rotation of 30 the scraper arms 13 around the shaft 5, it will be necessary for said blades to separate or move laterally away from each other. It is also evident that force will be required 35 to hold the scraper blades 18 positioned as shown at the left in Fig. 1 while performing the scraping action. With the arrangement described, when the scraper blades are moved in a clockwise direction in respect to Fig. 2, toward their operative positions, the 40 opposite or inoperative blades 18 will come into engagement with the cams 27 and the latter will force the engaged blades outward and the operative blades inward to the operative positions shown at the left in Fig. 1, 45 and the bevel on the stop rollers 19, acting on the inoperative blades 18, will prevent the operative blades at the left from being forced too nearly together or so closely together as to come into contact with the 50 spade-carrying arms 11. Also, the rollers 19, operating as just described, will intercept rotation of the double-ended arms 13 around the shaft 5 and will stop and yieldingly hold the operative scraper blades positioned as shown at the left in Fig. 1.

If, while performing the scraping or 55 scraper-cleaning action, a rock or the like should be wedged against an operating scraper blade, the excessive force will cause the particular arm 14 to rotate on the shaft 5. To permit this rotation of the arm, it is necessary to press the cooperating stop collar 19 out of the path of movement of the so-called inoperative blade, and it will be 60 understood that the tension of the spring 29

will be such that this action will take place under less force than that required to break any of the parts. The spring 24, however, acting through the stop roller 19, will exert sufficient force to prevent rotation of the 70 arm when the scraper blades are performing any normal or ordinary scraping action. When an inner or inoperative scraper blade has been forced past its cooperating stop roller 19 and below the lower extremity of 75 the cooperating cam 27, the pressure of earth on the outer or operative scraper blades will move the latter laterally away from the chain so that neither it nor its carrying arm 13 will be engaged with the chain 80 in passing the line of the chain. However, if the dirt should not produce this movement, no harm would be done because the scraper arm would be released and would move freely outward when brought into any 85 contact with the chain. When one of the scrapers has been tripped as above described, its carrying arm 13 will make one-half rotation and will be again stopped by the cooperating roller 19. 90

With the above described arrangement, it is not necessary that when one scraper is tripped that the other also be tripped, for the two scrapers are capable of independent rotation, independent oscillation and independent tripping actions. 95

What I claim is:

1. In an excavating mechanism, the combination with a scoop-equipped excavator belt, of a rotary scoop-cleaning device having circumferentially spaced scraper blades adapted to be operatively positioned in succession, the said cleaning device having a lateral swinging as well as rotary motion, and a yielding stop normally operative on 100 said cleaning device and adapted to yield and clear the same under excessive pressure. 105

2. In an excavating mechanism, the combination with a shaft, a wheel on said shaft, a scoop-equipped excavator belt movable over said wheel, a scoop-cleaning device rotatively mounted around the axis of said shaft and having circumferentially spaced scraper blades adapted to be operatively positioned in succession, said cleaning device having a lateral swinging as well as 110 rotary motion, and a yielding stop normally operative on the inactive scraper portion of said cleaning device and adapted to yield and clear the same under excessive pressure. 115

3. The structure defined in claim 1 in further combination with a relatively fixed cam member operative on said cleaning device to normally hold the same with one scraper blade positioned for action but permitting 120 said cleaning device to swing laterally when the latter is rotated.

4. The structure defined in claim 2 in further combination with a relatively fixed cam member operative on said cleaning de- 130

vice to normally hold the same with one scraper blade positioned for action but permitting said cleaning device to swing laterally when the latter is rotated.

5 5. The structure defined in claim 3 in which said yielding stop is in the form of a spring-pressed roller cooperating with said cam member to normally hold said cleaning device against lateral swinging movements.

10 6. The structure defined in claim 1 in which cleaning devices of the character therein defined are arranged one on each side of said excavator belt.

15 7. The structure defined in claim 3 in which cleaning devices of the character therein defined are arranged one on each side of said excavator belt.

20 8. The structure defined in claim 2 in which said yielding stop comprises a spring-pressed receding spindle held against rotation, and a stop roller journaled on said spindle.

25 9. The structure defined in claim 3 in which said stop device comprises a spring-pressed receding spindle held against rotation, and a stop roller journaled on said spindle, the said cam devices being supported from said non-rotary spindle.

30 10. In an excavating mechanism, the combination with a shaft, a wheel on said shaft, an excavator belt movable over said wheel and provided with outstanding arms equipped at their outer ends with curved excavator spades projecting on both sides 35 of said arms, sleeves rotatively mounted on said shaft adjacent the opposite sides of said wheel, arms intermediately pivoted to said sleeves, scraper blades on the outer ends of said arms operating to clean the concave 40 surfaces of said excavator spades, and yielding stops and relatively fixed cam elements operative on the inactive scraper blades to hold the active scraper blades in operative

positions against both rotary and lateral movements.

45 11. In an excavating mechanism, the combination with a shaft, a wheel on said shaft, an excavator belt movable over said wheel and provided with outstanding arms equipped at their outer ends with curved excavator spades projecting on both sides 50 of said arms, sleeves rotatively mounted on said shaft adjacent the opposite sides of said wheel, arms intermediately pivoted to said sleeves, scraper blades on the outer ends 55 of said arms operative to clean the concave surfaces of said excavator spades, a transverse non-rotary spring-pressed receding spindle adjacent the inactive scraper blades, and cooperating stop and cam-acting devices on said spindle operative on the inactive blades to yieldingly hold the same 60 and the active blades against both rotary and lateral movements.

65 12. In an excavating mechanism, the combination with a shaft, a wheel on said shaft, an excavator belt movable over said wheel and provided with outstanding arms equipped at their outer ends with curved excavator spades projecting on both sides 70 of said arms, sleeves rotatively mounted on said shaft adjacent the opposite sides of said wheel, arms intermediately pivoted to said sleeves, scraper blades on the outer ends 75 of said arms operative to clean the concave surfaces of said excavator spades, a transverse non-rotary spring-pressed receding spindle adjacent the inactive scraper blades, and beveled stop rollers and fixed cams on said spindle operative on the inactive scraper 80 blades to hold the same and the active scraper blades against both rotary and lateral swinging movements.

In testimony whereof I affix my signature.

GEORGE H. GREIMAN.
